DESIGN FOR A DIRECT-CONNECTED PRECISION CURVED TAIL TRIMMER

Michael Annick, Scranton, Pa., assignor, by
mesne assignments, to Wesel Manufacturing
Company, a corporation of Pennsylvania

Application January 19, 1934, Serial No. 50,453

Term of patent 14 years

To all whom it may concern:

Be it known that I, Michael Annick, a citizen of the United States, residing at 617 Harrison Avenue, in the city of Scranton, county of Lackawanna, State of Pennsylvania, have invented a new, original, and ornamental Design for a Direct-Connected Precision Curved Tail Trimmer, of which the following is a specification, reference being had to the accompanying drawing, forming part thereof.

The figure is a perspective view of the front of a direct-connected precision curved tail trimmer,

the predominant characteristic features of my new design, being shown in full lines.

The rear of the machine is identical with the front, with the exception of door A providing access to the interior of the frame, hand wheel B, control switches C, handle D and lever E.

I claim:

The ornamental design for a direct-connected precision curved tail trimmer, as shown and described.

MICHAEL ANNICK.
